ASH TRAY

George A. Black, William R. Lancaster, and Pete Dahl, Pine Grove, Calif.

Application July 10, 1940, Serial No. 344,818

1 Claim. (Cl. 131—237)

This invention relates to ash trays and has for an object to provide an ash tray which is operated simply by pressing downwardly on the top to cut off the burning end of a cigarette or receive its ashes.

A further object of the device is to provide an ash tray having its bowl filled with water or fireproof liquid to extinguish a cigarette and absorb smoke odor.

Another object of the device is to provide an ash tray having a valve to close the top of the bowl of the ash tray and make it smoke- and airtight after receiving cuttings, butts, matches and ashes.

A further object is to provide apparatus of this character which will be formed of a few strong, simple and durable parts, which will be inexpensive to manufacture, and which will not easily get out of order.

With the above and other objects in view the invention consists of certain novel details of construction and combinations of parts hereinafter fully described and claimed, it being understood that various modifications may be resorted to within the scope of the appended claim without departing from the spirit or sacrificing any of the advantages of the invention.

In the accompanying drawing forming a part of this specification:

Figure 1 is a cross sectional view of the device in normal or closed position.

Figure 2 is a top plan view of the device.

Figure 3 is a cross sectional view taken on the line 3—3 of Figure 1, looking in the direction of the arrows.

Figure 4 is a cross sectional view of the device in depressed or open position.

Referring now to the drawing in which like characters of reference designate similar parts in the various views, 10 designates a bowl adapted to contain water or other non-inflammable liquid 11. A flange rim 12, threaded on its inner periphery, threadedly engages the lower end of a cylindrical neck 13. The neck is provided with a pair of openings 14 on opposite sides thereof.

A hollow cylindrical cutter 15, open at its upper side, is slidably mounted in the neck 13 and is provided with openings 16 which, when it is in raised position, register with the openings 14 in the neck 13. The cutter 15 is normally supported

in raised position by coil springs 17 which are located between a cross bar 23 on the upper side of the cutter 15 and perforated lugs 18 formed on the inner side of the neck 13. Rods 19 are fixed to the cross bar 23 of the cutter and pass through the springs 17 and perforations in the lugs 18.

The lower edge of the neck 13 forms a seat 20 against which a conical valve 21 bears when the cutter 15 is in raised position. The apex of valve 21 is secured to the center portion of the cross bar 23 by a rod 22.

In use the smoker may cut the end off his cigarette by placing the lighted end into the 15 openings 14 and 16 in the sides of the cylindrical neck 13 and the slidably mounted hollow cylindrical cutter 15, pressing downwardly on the cross bar 23 on the cutter to the position shown in Figure 4. In this position of the parts, cuttings, 20 ashes, matches, and butts may be placed in the bowl 10. When pressure is released on the cross bar 23, the springs 17 force the cutter 15 back into the normal position as shown in Figure 1. In this position smoke and odors are sealed in 25 the container.

From the above description it is thought that the construction and operation of the invention will be fully understood without further explanation.

What is claimed is:

An ash tray comprising, a bowl, a cylindrical neck threadedly engaged with the bowl, a cutter slidably received in the neck, a cross bar on the top of the cutter, a stem connected to the cross bar and disposed axially in the cutter, a valve carried by the stem normally closing the bottom of the neck, said neck having a lateral opening and said cutter having a lateral opening to receive a cigarette when the openings are aligned, 35 said neck being provided with apertured inwardly extending lugs, pins carried by the cross bar slidably projecting through the apertured lugs, and helical springs sleeved on the pins engaged between the cross bar and the lugs for normally holding the cutter in position to aline said openings.
